UNITED STATES PATENT OFFICE.

AUGUST C. SCHOEN, OF PHILADELPHIA, PENNSYLVANIA, ASSIGNOR TO
STINSON BROS., OF PHILADELPHIA, PENNSYLVANIA, A FIRM.

MACHINE FOR PRINTING WARP.

No. 839,083.

Specification of Letters Patent.

Patented Dec. 18, 1906.

Application filed February 28, 1906. Serial No. 303,399.

To all whom it may concern:

Be it known that I, AUGUST C. SCHOEN, a citizen of the United States, residing in the city and county of Philadelphia, State of Pennsylvania, have invented a new and useful Machine for Printing Warp, of which the following is a specification.

My invention relates to a warp-printing machine; and it consists of a drum on which warp may be wrapped adapted to be reduced in diameter, whereby the warp may be readily removed. To this end the periphery of the drum is formed of movable parts or sections which may be drawn inwardly, provision being also made for restoring the periphery of the drum to its normal condition and locking it against improper motion, the means employed being hereinafter described, and the novel features of the same being pointed out in the claims.

It also consists of details of construction, as will be hereinafter described.

Figure 1 represents a perspective view of a warp-printing machine embodying my invention. Fig. 2 represents a partial side elevation and partial vertical section thereof. Fig. 3 represents a partial side elevation and partial vertical section of a portion of the machine, certain parts thereof being in different position from that shown in Fig. 2. Fig. 4 represents a perspective view of the means employed for removing the printed warp from the drum. Fig. 5 represents an end view thereof. Fig. 6 represents a vertical section of a portion on line $x-x$, Fig. 2. Fig. 7 represents a side elevation of a portion detached from Fig. 6.

Similar letters of reference indicate corresponding parts in the figures.

A designates a drum, and B the driving shaft thereof, the latter having its bearings on the frame C. On the inner periphery of the drum is the circular rack A', with which meshes the pinion A², whose shaft carries the pulley A³, which receives power from any suitable source, whereby the drum may be rotated.

The periphery of the drum is formed partly of movable sections D E, each of which is pivotally connected, as at F G, with the cross-bars H, which are secured to the interior of the remaining portion of the periphery, it being noticed that said sections D E are adapted to move inwardly, thus in a

measure collapsing the drum, as shown in Fig. 3. Pivotally connected with the section D are the racks J, which enter the drum and are engaged by the pinions K, whose shafts L have their bearings on the cross-bar H. On the shaft L is the sprocket-wheel M, around which passes the sprocket-chain N, which also engages with the sprocket-wheel P, whose shaft Q is mounted on a fixed member within the drum A and has connected with it the hand-wheel R for operating purposes.

Pivotally connected with the interior of the section E are the links S, which are slotted to receive the studs T on the cross-bars H, said links thus forming guides for said section E in its inward and outward motions.

It will be seen that the sections D E have their contiguous ends lap-jointed, as at U, whereby the section E is prevented from dropping below the section D in either of their positions, as shown in Figs. 2 and 3.

When the drum is in normal condition, as in Fig. 2, the warp may be wound around the same, as shown in Figs. 1 and 5, when the printing may be accomplished, the mechanism for which being omitted for purposes of clearness.

After the printing the yarn is to be removed. To this end the shaft Q is rotated, whereby the racks J are drawn inwardly and with them the section D. As the section E is now no longer supported by said section D, the former follows the latter when the parts assume the position shown in Fig. 3, thus in a measure collapsing the drum or reducing its diameter, whereby the yarn is loose on the drum and may be readily removed for further treatment.

Pivotally connected with a side of the frame C are the bars V, on the outer ends of which are the laterally-extending pins V¹. Latches or hooks V² are also pivotally connected with the bars V, the same being adapted to be engaged with studs V³ on the side of the frame, so as to retain the pins in operative position, as shown in Fig. 1 and the left side of Fig. 2; but said pin may be placed in inoperative position, as shown at the right side of said Fig. 2.

It will also be seen that the drum may be rotated so as to bring the shaft Q at what may be termed the "bottom" of the drum,

so as to be most convenient of access for operating the racks J regardless of the large size of the drum, the sections D E then being at the top of the drum, as shown in Fig. 2.

5 When the racks are operated in reverse direction, the section D is advanced outwardly, moving with it the section E, the two sections then being returned to their normal position, restoring the continuity of the drum, 10 after which the sections are locked from inward movement. For this purpose I employ the rod or bolt W, whose end portions are adapted to enter eyes or sleeves X as its bearings, which depend from the shaft L, on which 15 the pinions K are mounted, said rod having connected with it intermediate of said bearings the lever Y, which is mounted on a fixed member and held in operative position by the spring Z, which is suitably applied to said rod 20 and its sleeves.

The rod W has connected with it a casting or head W', on which is the bolt W², the latter being adapted to enter an opening in the adjacent rack J, and thus render the rack immovable, whereby the section D is firmly held in its normal position. When, however, 25 the lever Y is properly operated, the bolt W² is withdrawn from the rack, thus releasing the latter, after which the shaft Q may be rotated to open the sections D E, as previously 30 described.

When the warp A⁸ is removed from the drum, it may be of the form of a loop, as in Fig. 4, when bars A⁴ are inserted in the ends 35 of the loop, whereby the warp may be carried to and fitted on the sleeves V⁴, which are supported on the pins V', after which the warp may be tied at intervals and then be removed from said pins, so as to be easily taken elsewhere without dragging or being otherwise injured.

The drum has its periphery covered by material, such as oil-cloth, as shown at A⁵, Figs. 1, 4; and 6. This is removed with the printed warp from the drum, (see Fig. 4,) the oil-cloth being afterward disconnected from the warp when the latter has been printed.

The bars A⁴ are each provided with a groove A⁶, so that when the warp is wound around the 40 same it may be held thereon by the action of the rod A⁷, which presses the warp into said groove, the bar and rod being grasped by hand, as shown at the right of Fig. 4. By these means the warp is prevented from slipping, and the colors in the warp are retained 45 in alignment.

The means for supporting the warp or yarn after it is removed from the drum form the subject-matter of another application for 50 patent, Serial No. 340,763, filed October 26, 1906.

Having thus described my invention, what I claim as new, and desire to secure by Letters Patent, is—

65 1. In a machine for printing warp, a drum

having in its periphery a collapsible portion of pivotally-mounted sections adapted to be moved inwardly to reduce the diameter of the drum, a rack pivotally connected with one of said sections, a gear coöperating with 70 said rack and an endless belt and actuating means within the drum for operating said gear.

2. In a machine for printing warp, a drum having in its periphery a movable section, 75 means on an adjacent member on which said section is mounted, a bar connected with said section, a pinion engaging said bar, a wheel on the shaft of said pinion, an endless belt, a wheel mounted in said drum, said belt passing around said wheels and a hand-operated device connected with the last-named wheel.

3. In a machine for printing warp, a drum having in its periphery a collapsible portion of pivotally-mounted sections adapted to be 80 moved inwardly to reduce the diameter of the drum, a rack pivotally connected with one of said sections only and constructed to operate both sections, a gear coöperating with said rack and means in the drum for operating said gear, the second section being mounted to be actuated outwardly by the engagement therewith of the first-mentioned section and a movable guide for the second section connected with a member within the 85 drum.

4. In a machine for printing warp, a drum having in its periphery a collapsible portion, means on an adjacent member on which the sections of said collapsible portion are mounted, means connected with one of said sections and means for operating the same and comprising a hand-operating device within the drum, a shaft therefor, an endless belt connected with said shaft and with said operating means whereby the collapsible portion is operated in closing by the actuation of one of its sections only, and a locking device for holding said sections in their normal position.

5. In a machine for printing warp, a drum having in its periphery a movable section, means on an adjacent member on which said section is mounted, a bar connected with said section, a gear-wheel engaging said bar, a 115 sprocket-wheel on the shaft of said gear-wheel, an endless belt or chain, a sprocket-wheel mounted in said drum, said belt passing around said sprocket-wheels and a hand-wheel connected with the last-named 120 sprocket-wheel.

6. A machine for printing warp having in its periphery a movable section, a bar for operating said section, a gear-wheel engaging said bar, a bolt adapted to interlock said bar, 125 a bearing for the ends of said bolt and a lever connected with said bolt intermediate of said bearings and being mounted on a member on the drum.

7. In a machine for printing warp, a drum 130

having in its periphery, movable sections, adapted to decrease the periphery of the drum, the contiguous ends of said sections being lap-jointed and said sections mounted to have said contiguous ends supported one upon the other, means connected with only one of said sections for restoring said sections

to their normal positions by simultaneous operation and a locking device engaging a member of said restoring means.

AUGUST C. SCHOEN.
